ATTORNEY

UNITED STATES PATENT OFFICE.

JOHN WILL RICHARDS, OF LOGMONT, KENTUCKY.

CHECK-HOLDER.

1,263,115.

Specification of Letters Patent. Patented Apr. 16, 1918.

Application filed January 24, 1917. Serial No. 144,230.

To all whom it may concern:

Be it known that I, JOHN W. RICHARDS, a citizen of the United States, residing at Logmont, in the county of Bell and State 5 of Kentucky, have invented new and useful Improvements in Check-Holders, of which the following is a specification.

This invention relates to a check holder and more particularly to a holder for the 10 checks attached by miners to the cars used to convey coal from the mine galleries to the tipple.

The primary object of the invention is to provide a holder for checks of this character 15 which may be arranged within and connected with the bottom of a car for this purpose and is so constructed that a check placed therein before the car is loaded cannot be removed from the holder until the 20 car is dumped, thus preventing the loss of the checks, or the purloining of the same during the transportation of the coal.

With these and other objects in view, the invention resides in the novel combination 25 and arrangement of parts, which will be hereinafter described and particularly pointed out in the claims.

The preferred embodiment of the invention has been illustrated in the accompanying 30 drawing, although no restriction is necessarily made to the precise details of construction therein shown, as changes, alterations, and modifications, within the scope of the claims may be resorted to when 35 desired.

In the drawing:

Figure 1 is a view showing the improved check holder applied to a mining car.

Fig. 2 is a view showing the check carrying arm in raised position.

Fig. 3 is a longitudinal sectional view through the holder.

Fig. 4 is a cross section on the line 4—4 of Fig. 2.

Like characters of reference denote corresponding parts throughout the several views in the drawing.

Referring now to the drawing in detail, the letter A designates a car of the type 50 commonly used to convey coal from the mine galleries to the tipple and having arranged within and connected to the bottom thereof, the improved check holder 6.

The check holder 6 is provided with an 55 attaching plate 7 formed from any suitable material and connected with the bottom of

the car A by means of fastening elements 8, such as bolts, or the like, said attaching member having a beveled end 9 and is further provided in its upper face with a longitudinally extending recess 10 provided 60 at one end with an upwardly and inwardly curved portion 11, and at its other end with a reduced extension 12, said extension opening out at one end of the plate 7. The bottom wall of the recess 10 has formed therein a socket 13.

A check carrying arm 14 to be received in the recess 10 is provided with a rounded end 15 to extend beneath the curved end 70 wall of the recess 10 and is provided at its other end with a reduced portion 16 extending within the reduced portion 12 of the recess and serving as an actuating handle by means of which the check carrying arm 75 may be turned about its pivotal connection 17 with the attaching member, said turning movement of the check carrying arm being limited by an edge 18 of the rounded end of the recess 10. 80

The check carrying arm 14 has formed therein a recess 19, which when the arm is received in the recess 10 when in its lowered position registers with the socket 13 in the attaching member 7. 85

A pair of resilient plates 21 are arranged upon opposite sides of the recess 19 and connected with the check carrying arm 14 in any suitable manner, each of said plates being provided with a finger 22 extending 90 within the recess 19, so that when a check 23 is inserted within the recess 19, it will be engaged by the fingers 22 and held therein.

When the improved check holder has 95 been applied to a car as shown in Fig. 1 in the drawing and the car is to be filled with coal, the miner filling the car raises the check carrying arm 14 and inserts the check 23 in the slot 19 between the fingers 100 22, after which the arm is again lowered and received in the recess 10 and the car filled.

When the car reaches the tipple and is dumped, the check may be removed from 105 the holder by raising the arm 14 and releasing the check from engagement with the fingers 22, thus insuring the safe passage of the check from the galleries to the tipple.

Having thus described the invention, 110 what is claimed as new is:

1. In a device of the class described, a

plate having a beveled end and a recess in its top extending longitudinally thereof, said recess having upwardly and inwardly curved wall at one end thereof and a reduced extension at its opposite end opening out through an end of said plate, a check carrying arm swingingly mounted in said recess having a round end extending beneath the curved end wall of said recess, 10 and an operating handle on said arm adapted to be received in said extension.

2. In a device of the class described, an

attaching plate having a longitudinally extending recess in the top thereof and a socket opening out through the bottom of 15 said recess, an arm in said recess pivotally connected adjacent one end thereof with said plate having a recess therein registering with the socket in said plate, and plates on said arms having clamping hinges 20 thereon extending within the recess in said arm.

In testimony whereof I affix my signature.
JOHN WILL RICHARDS.

Copies of this patent may be obtained for five cents each, by addressing the "Commissioner of Patents, Washington, D. C."
